[**] Term: **14 Years**

[57] CLAIM

[21] Appl. No.: **55,200**

The ornamental design for a combined vehicle safety-belt
buckle cover and a tongue plate housing cover, as shown and
described.

[22] Filed: **May 31, 1996**

DESCRIPTION

[51] LOC (6) Cl. **02-07**

FIG. 1 is a front elevational view of a combined vehicle
safety-belt buckle cover showing my new design. The cover
is shown inserted over a safety-belt buckle which is shown
by broken lines for illustrative purposes only and forms no
part of the claimed design;

[52] U.S. Cl. **D2/639; D11/200**

FIG. 2 is a front elevational view thereof;

[58] Field of Search **D11/200, 201,**

FIG. 3 is a top plan view thereof; the bottom plan view being
a mirror image thereof; and,

D11/218; D2/639; 297/482; 24/633; D8/395

FIG. 4 is a right side elevational view thereof; the left side
elevational view being a mirror image thereof.
